UNITED STATES PATENT OFFICE.

MAX WORHATCH, OF PITTSBURGH, PENNSYLVANIA.

AEROPLANE.

1,297,286.

Specification of Letters Patent. Patented Mar. 11, 1919.

Application filed October 22, 1918. Serial No. 259,201.

To all whom it may concern:

Be it known that I, MAX WORHATCH, a citizen of the United States, residing at Pittsburgh, in the county of Allegheny and 5 State of Pennsylvania, have invented new and useful Improvements in Aeroplanes, of which the following is a specification.

This invention relates to an aeroplane, and one of the chief objects is to more effectively 10 control the machine during the operation of ascending and descending.

A further object is to provide stabilizing means whereby more effective control is obtainable when the machine is traveling on a 15 straight course.

Briefly described, the machine includes a body portion, plurality of forward planes, a plurality of rear planes, and an intermediate plane, the latter being especially designed 20 for stabilizing purposes; the machine further includes an engine driving a forward propeller, and also adapted to drive at times a propeller rotating on a vertical axis, and designed for use when ascending 25 or descending. Another feature of importance is the provision of gas containers so located that in the event of accident to the engine or any part of the mechanical driving or supporting means, descent may be 30 gradual and without serious injury to the machine or to the operator.

In the drawings,

Figure 1 is a view of the machine in side elevation, and Fig. 2 is a top plan view.

35 The body of the machine is designated 10 and is mounted upon wheels 12 at the forward portion and wheels 13 located near the rear. The forward planes are designated 15 and 16 and the rear planes as shown at 17 and 18. At an intermediate position is a 40 stabilizing plane 20. The engine is shown conventionally at 24 and drives through suitable connections shaft 25 carrying a forward propeller 26. This propeller may be thrown 45 out by means of a clutch 27 under the control of a lever 28.

The vertical shaft 30 carries a propeller 31 designed for use in ascending, and which may also be used in descending, for retard-

ing the movement of the machine under the 50 action of gravity. The vertical shaft is driven by means of a gear wheel 32 meshing with a gear wheel 33, the latter being mounted on shaft 25 carrying the forward propeller. The propeller carried by the vertical shaft may be thrown out through the 55 operation of a clutch 35 under the control of a lever 36.

A horizontal rudder is under the control of suitable operating means shown conventionally at 37, the rudder being designated 38. A vertically located rudder or vane 40 is under the control of means shown conventionally at 41. A seat for the operator is shown at 43, and seats for passengers are 65 designated 44.

In order to provide for the gradual return of the machine to the ground in the event of accident to the driving mechanism, I provide a plurality of gas containers, which 70 may be deflated under usual conditions, but which will be filled with gas when the aviator is about to undertake a flight under unusual or hazardous conditions. Two of these gas bags are located between the forward 75 planes, and at the ends thereof, being designated 45 and 46. A third gas container 48 is located centrally of the machine and near the rear planes. The arrangement of these gas containers is especially important with 80 reference to the several planes, as they serve to stabilize the machine, preventing the latter from being seriously influenced by air currents.

Having thus described my invention, I 85 claim:

1. In a device of the class described; a body portion, a plurality of forward planes mounted thereon, a plurality of planes at the rear of the body, guiding means, a forward propeller, a propeller rotating on a vertical axis, means for throwing the propellers into operation separately, and gas containers located below the ends of the upper forward plane and a gas container 95 located near the lower rear plane and centrally thereof.

2. In a device of the class described, a

body portion, a plurality of forward planes, gas containers located below the ends of the upper forward plane, a plurality of planes at the rear of the body portion, an intermediate plane located at the rear of the forward planes and transversely of the body, a gas container located along the line of the

body and near the rear plane, guiding means, a lifting propeller, a driving propeller, and means controlling the propellers independently. 10

In testimony whereof I affix my signature.

MAX WORHATCH.
